UNITED STATES PATENT OFFICE

2,076,426

STYLE AND CLOTH DESIGN ILLUSTRATOR

Joseph Caswell and Kazimierz Elechuk, Windsor,
Ontario, Canada

Application July 3, 1936, Serial No. 88,720

4 Claims. (Cl. 35—53)

In interest to the tailoring industry there has always existed a decidedly urgent need for a device or some means whereby the customer may have the privilege of viewing the image of a man or a woman as the case may be, actually displaying the particular pattern he or she may select, and in this manner it may be readily determined by the customer if a certain color and design of the cloth selected would be attractive and be coming to him after it is made up in a complete suit of clothes.

This invention fully meets this requirement and the principal object thereof is to provide a pair of spaced-apart plate glass panels. Upon the face of one of said panels will appear a front view of a gentleman outlined as though wearing a stylish suit, and upon the face of the opposite panel will appear a rear view of the same person and the entire background of both panels will be opaque with both of the outlines being clearly transparent, and by inserting a cloth of the selected pattern intermediate said panels the customer may readily observe how the pattern would appear when made up in a suit of clothes from a front view, and by turning the panels so as to expose the opposite panel a rear view will likewise appear for this purpose.

The invention possesses further advantages that will become apparent during the course of the following detailed description, illustrated throughout the accompanying drawings, and more fully pointed out in the appended claims.

With reference to the drawings:

Figure 1 is an elevation of one of the panels showing a front view of a gentleman; and Figure 2 is a similar elevation showing the front view of a woman.

Figure 3 is a vertical section taken upon line 3—3 of forthcoming Figure 5.

Figure 4 is a fragmentary view of the pair of panels and showing the spacer means therefor.

Figure 5 is an elevation of a panel opposite the one in Figure 1, and showing the rear view of a gentleman; and Figure 6 is a similar elevation of the panel opposite the one in Figure 2 and showing the rear view of a woman.

Figure 7 is a section taken upon line 7—7 of Figure 5.

Figure 8 is a greatly enlarged section of the top portion of a quantity of cloth and indicating the metallic support therefor.

Figure 9 is a greatly enlarged section of the bottom portion of the cloth and showing the support therefor.

55 The invention comprises a device wherein a

pair of plate glass panels is provided which is positioned in vertical arrangement and being in spaced apart relation.

One of the panels designated by the numeral 1 presents the outline of a gentleman attired in a stylish suit as at 2. The opposite panel 3 presents a rear view of a gentleman thus attired.

An independent pair of plate glass panels is provided, comprising panel 4 presenting the outline of a woman attired in a stylish coat suit as at 5, the opposite panel 6 presents a rear view of the woman thus attired.

The outlines of the gentleman and woman so described are accomplished by the use of preferably black paint placed upon the surface of a perfectly clear transparent glass, and the entire background of the panels upon the face thereof is completely covered with white paint as at 7, and in this manner it is understood that the respective outlines of both characters will remain at all times transparent while said background remains permanently opaque, the purpose of which will presently be explained.

The head, hands, shoes, stockings or other articles will present their natural colors respectively, thereby rendering these portions permanently opaque.

A number of designs or patterns of tailoring cloth is customarily provided by all tailors, and it is an object of the invention to provide a piece of such cloth such as A, adequate proportion so as to completely cover the rear surface of the respective panels 1 and 3, and in this manner said cloth will be clearly exhibited through the clear glass occupied by the human characters and the customer may visualize how this particular pattern will appear upon himself when it is made up in a suit of clothes.

Each of the patterns of cloth is provided with metal tube 8 having extended portion 9, and the edge of cloth A is doubled over and secured thereto by rivets 10, or in any other approved manner and as indicated in Figure 8.

The lower edge of cloth A is doubled over and is secured to elongated metal U member 11 by rivets 12, or in any other approved manner and as indicated in Figure 9.

As previously described the panels are arranged in pairs and are rigidly retained in spaced apart relation by spacer 13 upon the sides thereof and spacer 14 at the bottom of the same.

The cloth panel is easily manipulated by the tubular upper part which is wide enough not to descend between the plates. The bottom member is sufficiently narrow to enter between the 55

plates and has sufficient weight to fall easily and will therefore hold the cloth smoothly suspended.

It is further understood that the same method is employed for displaying the front and rear of 5 the woman character for this purpose.

While in one pair of the panels the front and rear views of the gentleman character is illustrated, the combination of a front or rear view of the gentleman and woman characters may be 10 used, or in fact any combination of characters may be employed consistent with the requirements of the tailor or otherwise.

In conclusion it may be added that any changes that may become necessary during any probable 15 further development of the invention for the market would be limited by the scope of the claims and by prior art.

Having thus fully described our invention, what we claim as new is:

- 20 1. In a display device, a pair of parallel spaced panels having transparent portions therein, a piece of fabric removably positioned between the panels and visible through said transparent areas, means for freely suspending the piece of fabric 25 between said panels and a weighted member attached to the lower edge of the fabric for maintaining the latter in a smooth and unwrinkled condition while suspended between the panels.
2. In a display device, a pair of paralleled 30 spaced panels having transparent areas therein representing the silhouette of a clothed human figure, a piece of fabric removably positioned between the spaced panels and visible through said transparent areas, and a member attached to the

upper edge portion of the piece of fabric adapted to rest upon the upper edges of the spaced panels for suspending the fabric between the panels.

3. In a display device, a pair of parallel spaced panels having transparent areas therein representing the silhouette of a clothed human figure, a piece of fabric removably positioned between the spaced panels and visible through said transparent areas, and a member attached to the upper edge portion of the piece of fabric adapted to rest upon the upper edges of the spaced panels for suspending the fabric between the panels, a weighted member attached to the lower edge portion of the piece of fabric also for disposition between the panels for maintaining the fabric 10 in a smooth and unwrinkled condition while suspended between the panels. 15

4. In a display device, a pair of parallel spaced panels having coating transparent portions representing the silhouette of the front and back of 20 a clothed human figure, a piece of fabric, a suspension member attached to the upper edge portion of the fabric for rest upon the upper edges of the spaced panels whereby the piece of fabric will be removably suspended between the panels 25 and visible through the transparent portions, and a weight member attached to the lower edge portion of the fabric also for disposition between the spaced panels for maintaining the piece of fabric in a smooth and unwrinkled condition 30 while suspended between said panels.
